UNITED STATES PATENT OFFICE

JOHN C. MALCOLM, OF WOLLASTON, MASSACHUSETTS, ASSIGNOR TO BAY STATE FISHING COMPANY, OF BOSTON, MASSACHUSETTS, A CORPORATION OF MASSACHUSETTS

TRAWLING GEAR

Application filed May 3, 1930. Serial No. 449,470.

This invention relates to an improved form of net trawling gear, more particularly of the type which is provided with panels or doors to assist in holding the net open, and 5 widening the area from which fish may be induced to pass into the mouth of the net.

The present invention affords an improved means of conveniently connecting the panels and net to the boat and to each other so 10 that the gear may conveniently be drawn in to permit the emptying of the net without undue interference by the panels. To these ends, a tow hawser may be provided which is connected to each panel and to a tow 15 cable having its intermediate part connected to the net, while having one end connected to the tow hawser and the other end connected to the back of the panel. Preferably the panel is detachably connected to the tow 20 hawser; accordingly the hawser may be drawn in and the panel disconnected therefrom, whereupon continued movement of the tow cable results in drawing the net to the boat so that the contents of the net may be 25 discharged without necessitating the disconnection of the tow cable from the back of the panel, while there may be a permanent connection between the hawser and the tow cable. This arrangement permits the net 30 towing strains to be divided between two sections of the tow cable, one of which is connected to the panel and the other of which is connected to the hawser and permits a part of the towing strains to be imposed upon 35 the panel and its connections while the remainder of the same are received by the section of the towing cable that is directly connected to the hawser.

Preferably a short connection may be provided 40 between the inner face of the panel and the two cable which may include a short chain having a C-shaped element or hook at its end which is engageable with a ring at the end of the hawser, this ring also permanently engaging a link of a chain which forms

a continuation of the tow cable. Preferably a bridle or substantially triangular bracket may be pivotally connected to the back of the panel and may receive a loop at the end of the tow cable, thus affording a permanent connection between these parts. 50 The net may provide a connection permitting the ready relative movement of the tow cable in relation to the wing of the net. This connection may comprise, for example, a suitable pulley block having a grooved pulley receiving the cable so that the cable may readily move over the pulley as the net is being drawn to the boat.

In the accompanying drawing:

Fig. 1 is a somewhat diagrammatic view 60 of my improved trawling gear, certain parts such as the panels and their connections being exaggerated in size for clarity of illustration;

Fig. 2 is an enlarged top view of the panel and the connections between the same and between the hawser and the tow rope;

Fig. 3 is an elevational view of the same; and

Fig. 4 is an elevational detail of the connection between the cable and net which readily permits relative movement therebetween. 70

Referring to the accompanying drawing, and first more particularly to Figure 1, the numeral 1 designates a boat to which my trawling gear may be connected; this gear includes a pair of tow hawsers 2 which have rings 3 at their outer ends for connection to the panels and the tow rope. Each panel 4 may be provided with a metal shoe or weight 5 and has the inner face of the end portion which is remote from the net provided with means for connection to the tow hawser. 75 Preferably for this purpose a pair of bridles or triangular metal elements 7 may have pivotal connections 8 with the inner surface of the panel and may have their juxtaposed apex portions received in a metal ring 9 that forms the end link of a connecting chain 10. The 80 85 90

opposite end of chain 10 is secured to a C-shaped element or hook 12 which is detachably engaged with the ring 3 at the end of the tow hawser.

5 The tow cable 16 is provided with a continuation in the form of a short chain 18 which is permanently connected to the ring 3. The intermediate part of each tow cable 16 is received in a grooved pulley 19, Fig. 4, which 10 is included in a pulley block 20 connected to the wing of the net 21. This net may be of any suitable form, and as shown has an upper portion provided with floats 22 to aid in holding the mouth of the net open.

15 Each tow cable also has a looped end portion 23 which may be permanently engaged with a triangular bridle 24 which is pivotally connected to the outer face of the panel 4 by means of metal elements 25 which are 20 disposed near the end of the panel that is closer to the net. It is evident that during the normal use of this trawling gear the boat 1 is moving in the direction of the arrow of Fig. 1, and that the towing hawsers 2 are 25 effective in drawing both the panels 4 and the net 22, the bridles 7 and 24 being so disposed in relation to the hawser and cable that the panels 4 incline forwardly and outwardly in relation to the direction of boat 30 movement and therefore are effective in holding the mouth of the net open. A portion of the net towing strain is transmitted from each line 2 directly through its connection to the towing cable 16, while the remainder 35 of this strain is transmitted through the corresponding panel 4 by means of its connections 7, 10 and 24 being received by the portion of the towing cable that is connected to the panel, thus, the towing cable has two 40 portions which receive the net towing strains.

When it is desired to draw the net inwardly to the boat, the hawsers 2 are first drawn inwardly by any suitable means such as winches until the ends of the hawsers are 45 positioned so that the panels 4 may be supported by suitable hoisting tackle or gallows, and the connections 12 then disengaged from the rings 3. Each towing cable then substantially forms a continuation of the corresponding hawser and is drawn inwardly, each 50 pulley 19 permitting relative movement of the cable and net so that the net is drawn inwardly until each pulley block is substantially in the region of the end loop 23 of the 55 cable whereupon the contents of the net may be discharged.

When the net is again to be let out to resume its normal position, the cables 16 are first unwound from the winches until 60 the rings 3 are brought into a position wherein they may again engage the connections 12. After these parts are suitably engaged, the panels 4 are released from their supporting gallows and the outward movement of the 65 hawsers 2 is effective in permitting the panels

to be spaced from the boat and to resume their normal positions.

From the foregoing it is evident that I have provided a trawling gear arrangement which permits the convenient discharge of 70 the contents of the net without interference by the panels or doors 4 and that it is only necessary to provide one detachable connection for each towing hawser in order to permit the convenient operation of the device in 75 the manner described above. Furthermore it is evident that this arrangement permits the convenient manipulation of each hawser and the corresponding towing cable as a single 80 substantially continuous unit so that a single winch may be employed for drawing both of these elements onto the boat. Furthermore this arrangement permits the net towing strains to which each hawser is subjected to be divided between the two end portions of 85 the towing cable, a part of this strain being transmitted directly from the hawser to the towing cable and the remainder thereof being transmitted through the panel and its 90 connections.

I claim:

1. Trawling gear comprising a net, a pair of hawsers, a tow line connected to each hawser and having its intermediate part connected to a side of the net, a panel associated with each hawser, each tow line having one end connected to the end of a panel nearer the net, and having an end connected to the hawser, and a connection between the inner face of each panel and a hawser. 100

2. Trawling gear comprising a net, a pair of hawsers, a pair of tow lines, each tow line having an end connected to the corresponding hawser, a panel associated with each hawser, a short connection extending from the inner face of the panel to the hawser, a connection between the hawser and one end of the tow line, and a connection between the outer face of the panel and the other end of the tow line, the intermediate part of the tow 110 line having a freely movable connection with the side of the net.

3. Trawling gear comprising a net, a hawser for connection to a boat, a panel adjoining the end of the hawser, a detachable connection extending from the inner face of the panel to the hawser end, a tow cable having one end connected to the hawser and the other end joined to a connection extending from the outer face of the panel, the intermediate part of the tow cable having a relatively movable connection with the net. 115

4. Trawling gear comprising a net, a tow hawser, a ring at the end of the hawser, a panel, a tow line having an end connected to the ring, a detachable connection between said ring and the inner face of the panel, the intermediate part of the tow line being movably connected to the net, and the other end of the tow line having a permanent connec- 120 125 130

tion with the outer face of the portion of the panel which is nearer the net.

5. Trawling gear comprising a net, a tow hawser, a ring at the end of the hawser, a panel, a tow line having one end connected to the ring and the other end connected to the panel, a net, a pulley secured to the net and receiving the intermediate part of the tow line, and a line joined to the inner face 10 of the panel and detachably connected to the ring.

Signed by me at Boston, Massachusetts, this first day of May, 1930.

JOHN C. MALCOLM.
